UNITED STATES PATENT OFFICE.

FRANCIS HICKMAN, OF READING, PENNSYLVANIA.

IMPROVEMENT IN FOLDING CHAIRS.

Specification forming part of Letters Patent No. 170,562, dated November 30, 1875; application filed September 18, 1875.

To all whom it may concern:

Be it known that I, FRANCIS HICKMAN, of Reading, in the county of Berks and in the State of Pennsylvania, have invented certain new and useful Improvements in Folding Chairs; and do hereby declare that the following is a full, clear, and exact description thereof, reference being had to the accompanying drawings and to the letters of reference marked thereon, making a part of this specification.

My invention relates to folding chairs; and it consists in the construction of the same entirely of straight pieces of material, and in such a manner that when folded the seat (which can be rigid or of flexible material) will lie flat in between the back of the chair, all as more fully hereinafter set forth.

In the accompanying drawings, Figure 1 represents a side view. Fig. 2 represents a perspective view of a side portion of the chair; and Fig. 3 represents a longitudinal section.

The supports for the chair consist of four (4) pieces of straight material, A A', pivoted together, and in the form of a saw-buck, and braced by the rounds b b b. The back is composed of two straight bars, B, connected by a bar at the top, and by a bar, E, at the bottom. These back bars extend suitably above and below the seat, as shown. C represents the seat, which can be of rigid material, such as wood or metal, or can be of flexible material, such as carpet, canvas, &c. This seat is pivoted at Y in between the bars B, and is also hinged by links x, or other suitable devices to the tops of the bars A. Directly below the seat C, at each side of the chair, is a double-acting hinge, e, which is connected at z z to the tops of the bars A and to the bars B. Upon the back edges of the bars A, just above the connecting-rounds b, a stop notch or catch, a, is attached to or formed with each bar. The back-bars B extend outside of the bars A', and when the chair is in position for occupancy, the brace-bar E of the back bears against the stops, notches, or catches a on the bars A, and supports the bars in proper position.

This chair may or may not be provided with arms. If arms are desired, either of the two styles shown can be employed.

In the forms shown in Figs. 1 and 2 a bar, m, is pivoted to the bar B, and an upright bar, n, is hinged or pivoted to the front of bar m. The lower end of bar n has a slot, g. On the standard A is a pin, b, which passes through the slot, so that the bar n can work up and down. When this bar is down its full length its end bears against a pin on the lower end of the back bar B.

In Fig. 3 the arm is shown made of three parts, m', m'', and n', the latter pivoted to the standard A.

In either form of arm the parts are made of straight material and fold parallel with the chair-back pieces B. The peculiarity in the fold of this chair is that the legs spread or separate at the bottom instead of closing together as in the ordinary camp-chair, and the back closes down upon the legs, with the seat in flat position between the back-bars.

With my chair a rigid seat can be used, or, if upholstery, &c., is used, the material does not fold, but is kept straight and stretched.

When the chair is folded, the bars which support it, and the back-bars, are on parallel lines with the seat in the back.

The double-acting hinges e accommodate themselves to the position of parts both in opening and closing.

This chair can be cheaply constructed, and when folded closes into a small compass, and is not liable to be easily broken in transportation.

Having thus fully described my invention, what I claim is—

The combination of the legs A', having catching devices a, and connected by links to the front of the seat C, the legs A hinged to the bars B, the seat C pivoted to the back-bars B, and the extended back-bars B having brace E, for engaging with the catches a, all substantially as set forth.

In testimony that I claim the foregoing I have hereunto set my hand this 30th day of August, 1875.

FRANCIS HICKMAN.
